C. L. OLD

GAS LIGHTER

Filed April 21, 1921

Fig. 1.

UNITED STATES PATENT OFFICE.

CLARENCE L. OLD, OF GILROY, CALIFORNIA.

GAS LIGHTER.

Application filed April 21, 1921. Serial No. 463,296.

To all whom it may concern:

Be it known that I, CLARENCE L. OLD, a citizen of the United States, residing at Gilroy, in the county of Santa Clara and 5 State of California, have invented certain new and useful Improvements in Gas Lighters, of which the following is a specification.

This invention has for its object the provision of a simple and inexpensive means 10 whereby gas may be ignited at a burner without the use of matches or other explosives and safety in the use of gas burners thereby assured. The invention seeks to provide a device for the stated purpose 15 which will be easily manipulated and which is not apt to get out of order and by which a spark may be produced at will at the gas burner so as to ignite the gas issuing therefrom. These stated objects and other objects 20 which will incidentally appear hereinafter are attained in such a device as is illustrated in the accompanying drawings and the invention resides in certain novel features which will be particularly pointed 25 out in the appended claim.

In the drawings—

Figure 1 is a view, partly in elevation and partly in section, of an apparatus embodying my invention;

30 Fig. 2 is an elevation of the resistance box with the cover removed;

Fig. 3 is a longitudinal section through the resistance box.

In carrying out my invention, I employ 35 a resistance box 1 which is provided with openings 2 at such points as may be deemed convenient through which fastening devices may be driven into the wall of a room in which the device is to be used, a backing 40 3 of insulation being interposed between the box and the wall, and the box also being preferably of insulating material. It will also be understood that collars or bushings of insulation will be fitted around the 45 fastening devices within the openings 2 so that the possibility of short circuiting through the material of the box will be avoided. In the upper end of the box is provided an opening for a leading-in conductor 4 which is to be connected to the ungrounded side of the house circuit and a bushing or collar 5 of insulation is fitted in the said opening around the conductor 4, as will be readily understood. The exposed 50 end 6 of this conductor is secured around a binding post 7 within the box and the said

post is insulated from the box by a washer 8 and a bushing 9, as will be readily understood. The box may be lined also with asbestos or other non-conducting material, as 60 indicated at 10. Upon the back wall of the resistance box, at the lower end thereof, I secure a block 12 of insulation and in the upper end of this block I secure a binding post 13, a resistance coil 14 being secured 65 to and extending between the posts 7 and 13, as shown. In the upper end of the resistance box and at the center of the same, I provide a binding post 15 which is also insulated from the back wall of the box by a 70 washer 8 and bushing 9 and this binding post 15 is connected with the post 13 by a metallic link 16. A third binding post 17 is mounted in the resistance box adjacent the upper end thereof and this binding post 17 75 is connected with the post 13 by a resistance coil 18. In the lower end of the insulating block 12 is provided a post 19 which forms the pivot or fulcrum for a switch arm 20 which is preferably a leaf spring and carries 80 a handle 21 playing in a slot 22 in the cover 23 of the resistance box, the said slot 22 being, of course, concentric with the pivot post 19. To the upper end of the post 19, I secure the bare end 24 of a conductor 25 85 which extends through an opening in the bottom of the resistance box and through an insulated bushing or ring 26 fitted in the said opening. The conductor 25 extends into a handle 27 of wood or other non-conducting 90 material and at the point of entrance a light spring 28 is coiled around the conductor so as to prevent breaking thereof by the bending of the same over the end of the handle. Within the handle 27 is a chamber 29 and 95 a leaf spring 30 is secured to the end of the conductor within the said chamber, as clearly shown in Fig. 1. A push button 31 is mounted in the side of the handle and connected with said spring so that pressure 100 upon the push button will cause the end of the spring to bear upon the inner end of a conductor 32 which is secured firmly in the end of the handle and projects therefrom. This conductor 32 is preferably a light rod 105 or stout wire and its extremity 33 is to be rubbed upon the gas burner when the device is to be used.

It is thought the manner of using the device will be readily understood. The conductor 4 is attached to the leading-in wire or the ungrounded side of the usual house

circuit and; when it is desired to light a gas burner, the point or conductor 32 is rubbed over the burner, while at the same time the button 31 is pressed inwardly so as 5 to carry the extremity of the spring 30 into contact with the inner extremity of the said point. Prior to the grasping of the handle 27 and the bringing of the point 32 into proximity with the burner, the switch 20 is 10 shifted so that its free end will engage one of the binding posts 7, 15, or 17 accordingly as the grounded side of the circuit is closer to or more remote from the gas burner. When the point 32 is brought against or rubbed 15 against the gas burner, a gap is formed in the circuit and a spark will be produced in said gap and the gas issuing from the openings of the gas burner will be ignited by said spark. When the free end of the 20 switch 20 is not touching one of the posts 7, 15 or 17, no current will flow through the apparatus, but, if the switch be shifted so that its free end engages the end of the binding post 7, current will flow from the 25 conductor 4 to said post 7 and thence through the switch member 20 to the post 19 and the conductor 25. In this position of the switch, the resistance coils are inactive but if the switch be shifted into engagement with the post 15, the current will 30 flow through the resistance coil 14 and thence through the link 16 to the post 15 and to the switch. In a like manner, if the switch be shifted onto the post 17, the current will 35 flow through the resistance coils 14 and 18 to the switch member 20 and the link 16 will be inactive.

The device is obviously simple and compact and may be produced at a low cost. 40 It may be secured upon the wall of a room

at any convenient point and the conductor 25 may be of any desired length so that the point or spark-forming conductor 32 may be easily brought into position adjacent any gas burner in the room. By my device the 45 use of matches will be rendered unnecessary and the gas may be lighted quickly and easily whenever desired.

The device may be used also where there is no house current by providing a battery 50 and connecting one terminal of the battery to the gas pipe, an insulated joint, of course, being provided in the pipe between the point of attachment of the conductor and the point where said pipe is grounded. The 55 opposite terminal of the battery will be connected to the conductor 4 and the device may then be manipulated in the same manner as when connected into a house circuit.

Having thus described the invention, what 60 is claimed as new is:

In an apparatus of the class described, a resistance box, a plurality of spaced contacts in one end of the box insulated therefrom, a leading-in conductor secured to one 65 of said contacts, a binding post secured in the opposite end of the box and insulated therefrom, electrical connections between said binding post and each of said contacts, a pivot post secured in the box adjacent said 70 binding post and insulated from the box and from the binding post, a conductor secured to said pivot post and leading from the box, and a lever arm fulcrumed on said pivot post and adapted to engage any one of 75 the spaced contacts.

In testimony whereof I affix my signature.

CLARENCE L. OLD. [L.S.]
